F. M. DOOLITTLE

RADIOTELEPHONY

Filed Feb. 21, 1924

Inventor
Franklin M. Doolittle
Seymour & Co. Inc.
Attn:

Patented Nov. 4, 1924.

UNITED STATES PATENT OFFICE.

FRANKLIN M. DOOLITTLE, OF NEW HAVEN, CONNECTICUT.

RADIOTELEPHONY.

Application filed February 21, 1924. Serial No. 694,388.

To all whom it may concern:

Be it known that I, FRANKLIN M. Doolittle, a citizen of the United States, residing at New Haven, in the county of New Haven and State of Connecticut, have invented a new and useful Improvement in Radiotelephony; and I do hereby declare the following, when taken in connection with the accompanying drawings and the characters 10 of reference marked thereon, to be a full, clear, and exact description of the same, and which said drawings constitute part of this application, and represent diagrammatically one form which an apparatus for practically 15 ing my invention may assume.

This invention relates to a method of transmitting and receiving radio telephonic impulses in such a manner as to evoke in the mind of the listener substantially the same consciousness of location of the source 20 of the sound or sounds as he would have obtained had he been personally present at the transmitting station. An important application of my invention is to the field of 25 radio telephone broadcasting, the end in view being to place the listener to a broadcasting program in the same acoustical relation with the performance as though he were present.

30 In the present broadcasting of entertainment and other matter by radio, use is made of some form of microphone pickup device which responds with approximate equality to a wide range of frequencies and 35 the circuits and apparatuses employed are so designed and organized that the waves radiated convey a very exact impression as to the true tone values to a listener with suitable receiving equipment for detecting 40 them. There is one serious defect in the reproduction of performances broadcast by radio in this way for, however true the tones themselves may be to the original ones, the listener is deprived of that consciousness of 45 location of the performer or performers which he would have were he present in person at the performance and hence the rendition is distorted and unnatural.

The purpose of my invention is to eliminate 50 the unnaturalness above described and to this end a method and apparatus are employed for transmitting and receiving by radio telephony, not only the tones which

are produced at a performance of whatever character or description, but those slight 55 differences in time of arrival of the sound at the two ears which the mind translates into impressions of location. By means of my invention a radio listener can have presented to his ears at a distant point a performance which simulates the original in all essential particulars.

My invention takes advantage of the auditory principle referred to with the end 60 in view of providing a method of and apparatus for transmitting and receiving the phase differences in the arrival of sounds at the ears of a listener present at the performance to a distant point by radio so that 65 the radio listener may obtain the same 70 acoustical impression as to the location of the source of the sound or sounds as though he too were present. To this end I employ two separate channels of radio transmission 75 which may be obtained in a variety of ways as, for example, by the use of two wave lengths or by employing a single wave length modulated at two superaudible frequencies which are in turn modulated by 80 the voice frequencies, two microphonic devices of suitable construction separated by substantially the ears of a human being, one of which is arranged to modulate the radiation of one channel and the other that of 85 the other channel so that two versions of 90 the same sound or sounds differing in the necessary phase relation, produce the consciousness of location when interpreted by the mind of the listener.

I also employ two radio receivers for the simultaneous reception on the two channels bearing the phase differentiated versions of 95 the performance. My invention further consists in employing two telephone listening devices, the right one of which is connected to the receiver associated with the channel with which the right microphone at the performance is connected and the left one with the receiver associated with the channel to which the left microphone at the performance is connected. With this arrangement the right receiver produces an 100 essential duplication of the vibrations reaching the right microphone and the left receiver of those reaching the left microphone 105 in their relative phase-relations as well as

in true tone-values. Hence, the ears of the listener are in effect transferred to the location of the microphones. If a telephone head set is employed and the left receiver 5 is associated with the right microphone and the right receiver associated with the left microphone the impression of location will be reversed, objects on the left appearing to be on the right and vice versa. Since 10 the location impression has been found to be due to the phase relation in the arriving of sounds at the two ears and is not dependent on the relative intensities of the sounds received by both ears considerable 15 variation in the signal strength in the two channels may be permitted without appreciably impairing the impression of location.

My invention will be understood by referring 20 to the accompanying drawing, which diagrammatically represents one form which an apparatus for practicing my invention may assume, on which 10, 11, 12 and 13 represent four different sources of sound, such as a quartet of singers. Within the 25 sound range of the sources of sound so designated I locate two microphones 14 and 15 of any suitable type and preferably separated from each other by a distance corresponding to that separating the ears of the 30 average individual, but this is not imperative, since the distance of the separation of these microphones may be varied according to circumstances, without departing from my improved method. The microphone 14 35 forms a feature of an independent radio transmitting apparatus, generally designated by T^1 , while the microphone 15 forms a feature of another radio transmitting apparatus generally designated by T^2 . Each 40 transmitting apparatus just described has the usual antennae 16 and the usual ground connection 17. The apparatus above described, it will be understood, is located at the broadcasting station. At the receiving 45 station I locate two receiving apparatuses R^1 and R^2 , each independent of the other, each having the usual antennae 18 and the usual ground connection 19, and respectively 50 provided with telephone receivers 20 and 21, adapted in any convenient manner to be fitted to the ears of the person who wishes to "listen in." The transmitting apparatus T^1 and the receiving apparatus R^1 are tuned in 55 consonance, while the transmitting apparatus T^2 and the receiving apparatus R^2 are tuned in consonance. Whether the tuning described is effected by differentiating the 60 wave lengths or by employing the same wave length modulated at two superaudible frequencies which are in turn modulated to the voice frequencies at the receiving station, they will remain distinct in the sense of providing two distinct, non-interfering 65 channels of radio communication. If the receiving apparatus R^1 should be tuned to

consonance with the transmitting apparatus T^2 and the receiving apparatus R^2 should be tuned to consonance with the transmitting apparatus T^1 , the impression of location will be reversed,—that is to say, the sources 70 of sound 12 and 13 would seemingly exchange places with the sources of sound 10 and 11 and vice versa, which would not, however, affect the ability of the apparatus to evoke mental impressions of location in 75 the mind of the listener.

In the use of the apparatus, the person "listening in" not only receives the tone values as in ordinary radio reception, but also receives a mental picture of the respective positions of the different sources of sound at the sending station, whether those sources of sound be persons singing or the pieces of an orchestra, and so on.

I claim:

1. In an apparatus for transmitting sounds by radio telephony, the combination with two sound pick-up devices so relatively positioned as to receive sound in a manner simulating the reception of sounds by the 90 ears of a human being; of two non-interfering channels of radio transmission respectively connected with the said pick-up devices.

2. In an apparatus for receiving sounds by radio telephony, the combination with two listening devices, one for each ear; of a double-channel radio telephone receiver for the simultaneous and non-interfering reception of two versions of the same sound, 100 the respective channels of the said double channel radio receiver being connected with the respective listening devices.

3. In an apparatus for transmitting and receiving sounds by radio telephony, the combination of two sound pick-up devices relatively positioned so as to receive sound in a manner simulating the reception of sounds by the ears of a human being; of two independent, non-interfering radio transmitting apparatuses connected with the respective sound pick-up devices, a double-channel radio telephone receiver for the simultaneous and non-interfering reception of the two 110 versions of the same sound which have been 115 picked up by the said sound pick-up devices, and two listening devices, one for each ear, respectively connected with the respective channels of the said double-channel radio telephone receiver.

4. A method of transmitting and receiving sounds by radio telephony with the effect of evoking in the mind of the listener a mental picture of substantially the relative location of the initial production of the various sounds, the said method consisting in transmitting the sounds from the point of their initial production through two independent non-interfering channels of radio communication and converging the sounds so 130

transmitted upon the respective ears of the
listener, whereby there is evoked in his mind
substantially the same consciousness of the
location of the origin of the various sounds
as would be actually apparent to a person
located at the scene of their origin.
In testimony whereof, I have signed this
specification in the presence of two subscrib-
ing witnesses.

FRANKLIN M. DOOLITTLE.
